UNITED STATES PATENT OFFICE.

JOHN C. VAN SLYKE, OF FORT COLLINS, COLORADO.

ELECTRIC TIME-SWITCH.

No. 875,017.

Specification of Letters Patent.

Patented Dec. 31, 1907.

Application filed July 12, 1907. Serial No. 383,498.

To all whom it may concern:

Be it known that I, JOHN C. VAN SLYKE, a citizen of the United States, residing at Fort Collins, in the county of Larimer and State of Colorado, have invented a new and useful Electric Time-Switch, of which the following is a specification.

This invention relates to electric time switches, and especially to switches of that general class used for the extinguishing and lighting of lamps in stores, factories, and other places for the purpose of effecting closing of the lighting circuit at any time during the evening and maintaining the circuit closed until daylight the next morning, although, of course, it is equally applicable for various other purposes, such, for instance as in the operation of time locks, or for a variety of circuit closing devices.

One of the principal objects of the invention is to provide a device that may be applied to an ordinary clock mechanism with but small expense, and a further object is to provide a device that may be very readily adjusted for the purpose of timing the opening and closing movements of the circuit.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a front elevation of an electric time switch constructed in accordance with the invention. Fig. 2 is a sectional plan view of a portion of the same on the line 2—2 of Fig. 1. Fig. 3 is an enlarged detail view of a portion of the mechanism.

Similar numerals of reference are employed to indicate corresponding parts throughout the several figures of the drawings.

The present embodiment of the invention is shown in connection with an ordinary clock having a timing train A and a striking train B, the controlling wheel 10 of the latter, however, being provided with but two notches 11 and 12 in place of the usual number, and the striking mechanism, that is to say, the gong and hammer, being removed.

Mounted on the arbor of the wheel 10 at a point in front of the main frame is a disk 16 carrying a crank pin 17 that is connected by a rod 18 to a switch arm 19. This switch arm is mounted on a hanger 20 depending from a plate 21 formed of insulating material and constituting the switch base, such plate being supported by a bracket 22 that is secured to the clock frame. Depending from the plate 21 are spaced contacts 23 which form the terminals of a circuit that is in part indicated by the wires 24 and which may include lamps or other translating devices and a source of electrical energy. When the pin 17 of the crank disk is in the lowermost position, the switch is open and remains open for any predetermined period of time, after which the disk 16 revolves to the extent of half a revolution, stopping with the pin in the uppermost position, and in this position the switch is closed and remains closed for any predetermined period of time.

Mounted on the hollow arbor *a* of the hour wheel is a sleeve 30, the friction between the sleeve and the arbor being such that the sleeve is rotated by the time train, although said sleeve may be revolvably adjusted in either direction without turning the arbor, and to effect this adjustment the sleeve is provided at its outer end with a milled disk 31 bearing numerals arranged in two opposed series from three to nine inclusive, these being disposed at equal thirty degree distances from each other.

To the rear end of the sleeve 30 is rigidly secured a pinion 33 that is provided in the present instance with twenty teeth, and mounted on the sleeve is a loose pinion 34 of the same diameter as the pinion 33 and bearing a corresponding number of teeth. The pinion 34 is held against a shoulder 35 on the sleeve by means of a small compression spring 36 that bears against the fixed pinion 33, and there is sufficient friction exerted on the pinion 34 to compel its rotation with the sleeve under ordinary conditions, but said pinion 34 is, also, arranged for independent rotative adjustment on the sleeve, and to accomplish this adjustment an arm 37 is employed, the arm being bent over the periphery of the disk 31 and being provided with a terminal point which may be moved opposite any of the numerals of one series of the disk, the position of this pointer determining the length of time which the switch is to remain in closed position, while the adjustment of

the disk as a whole with relation to the hour hand of the clock determines the time at which the switch shall be closed.

To prevent excessive adjustment of the arm 37 the disk is provided with a pair of stop pins 40, so that the arm 37 can only move over one series of numerals from three to nine, inclusive, and in the present instance therefore, the switch may be held closed for any period longer than three hours, or shorter than nine hours, and this period may be increased or diminished very readily by simple alteration in the dial numbers and gearing connections.

15 Projecting from the frame of the clock is a stationary arbor 42 on which are mounted two independently revoluble gears 43 and 44, each of which is provided in the present instance with forty teeth, the gear 43 intermeshing with the pinion 33, and the gear 44 intermeshing with the pinion 34. The pinion 43 carries a trip pin 45 and the pinion 44 a trip pin 46, and these pins are arranged to successively engage a tripper arm 47 that is carried by the arbor 48 of the tripping mechanism which controls the revolution of the notched wheel 10. As the pinions 33 and 34 are mounted on the hour hand arbor and are provided with twenty teeth and the gears 43 and 44 are provided with forty teeth it follows that the gears will rotate once each twenty-four hours.

In operation, the disk 31 is first turned until one of the fingers of the dial designating the hour at which the switch is to be closed is under the hour hand of the clock, while the pointer arm 37 is similarly adjusted in accordance with the length of time the switch is to remain closed. The adjustment of the dial and the arm serves to revolve the pinions 33 and 34, and the movement is transmitted to the gears 43 and 44, so that pins 45 and 46 are moved forward or back, so that the pin 45 shall trip the arm 47 at a certain time, and the pin 46 shall again trip the arm at another time, the distance between the two pins being determined by the length of time the circuit is to remain closed. If the switch be in open position 50 with the pin 17 in its lowermost position, the first tripping movement will rock the shaft 48 and raise the controlling arm from the wheel 10, so that the latter will be rotated by the actuating spring of the striking train, and the wheel 10 will make one half of a revolution or until the controlling arm enters the second or opposite notch of said wheel 10. The disk 16 likewise moves to the extent of half a revolution 55 and moves the pin 17 to the highest position, thus closing the switch, and the parts remain in this position until the pin 46 again trips the arm, when wheel 10 makes an-

other half revolution and disk 16 turns the crank pin 17 to the lowermost position, thus 65 breaking the circuit.

It is obvious that the device may be adjusted for the closing of the switch at any predetermined time and for maintaining it closed for any length of time.

The clock may be used as an ordinary time piece in an office, store, bank or other place, as well as for the purpose of operating the switch.

I claim:

1. In an electric time switch, a clock train including an hour hand arbor, a sleeve frictionally mounted thereon and independently adjustable, a numeral bearing disk at the outer end of said sleeve, and adjustable relatively to the hour hand, a pinion secured to the sleeve, a second pinion frictionally mounted on the sleeve and adjustable independently thereof, an adjusting arm secured to the second pinion and terminating adjacent to the periphery of the disk, a pair of independently revoluble gears intermeshing with said pinions and provided with trip pins extending inward from the adjacent faces of said gears, a switch member, an actuating device therefor, and a locking means for said actuating device, said locking means being under the control of said trip pins.

2. In an electric time switch, a clock train including an hour hand arbor, a sleeve frictionally mounted thereon and adjustable independently thereof, a numeral bearing disk at the outer end of said sleeve and adjustable relatively to the hour hand, a pinion secured to the sleeve, a second pinion frictionally mounted on the sleeve, a spring disposed between the two pinions and tending to force the second pinion against a shoulder on the sleeve, said second pinion being independently adjustable, an arm secured to the second pinion and having its outer end bent over the periphery of the disk, a pair of stop pins carried by the disk for limiting movement of the arm, a pair of independently revoluble gears intermeshing with the pinions and provided with trip pins extending inward from the adjacent faces of said gears, a switch member, an actuating device therefor, and a locking means for said actuating device, and a single tripper arm arranged to be successively engaged by both of the trip pins and serving to control said locking means.

In testimony that I claim the foregoing 120 as my own, I have hereto affixed my signature in the presence of two witnesses.

JOHN C. VAN SLYKE.
